UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

ONE-PIECE-STOCK TAKEDOWN FIREARM.

1,870,118.

Specification of Letters Patent.

Patented Mar. 1, 1921.

Application filed September 20, 1920. Serial No. 411,452.

To all whom it may concern:

Be it known that I, THOMAS C. JOHNSON, a citizen of the United States, residing at New Haven, in the county of New Haven and State of Connecticut, have invented a new and useful Improvement in One-Piece-Stock Takedown Firearms; and I do hereby declare the following, when taken in connection with the accompanying drawings and the characters of reference marked thereon, to be a full, clear, and exact description of the same, and which said drawings constitute part of this application, and represent, in—

15 Figure 1, a view in right-hand side elevation of a fire-arm embodying my invention.

Fig. 2, an enlarged broken plan view thereof showing the recoil collar entering 20 the groove in the stock, whereby its rear and front faces are utilized in taking the recoil and the counter-recoil.

Fig. 3, a broken view partly in right-hand side elevation and partly in vertical 25 section, showing the recoil-collar as mounted upon the receiver, the barrel as mounted in the receiver without contact with the recoil-collar, and the take-down screw and its bushing.

30 Fig. 4, an enlarged detached view partly in side elevation and partly in section of the take-down bushing.

Fig. 5, a detached reverse plan view thereof.

35 Fig. 6, a detached view in side elevation of the take-down screw.

Fig. 7, a detached view in front elevation of the recoil-collar.

Fig. 8, a detached view thereof in vertical 40 section.

Fig. 9, a detached broken view in side elevation of the forward end of the receiver.

Fig. 10, a corresponding view of the rear 45 end of the barrel.

Fig. 11, a view partly in transverse section on the line 11—11 of Fig. 2, and partly in elevation.

Fig. 12, an enlarged broken sectional view 50 on the line 12—12 of Fig. 11, showing the separation of the barrel and recoil collar by the receiver so that no part of the tilting stress caused by the collar, is transmitted to the barrel.

55 Fig. 13, a broken view partly in right-

hand side elevation and partly in vertical section of one of the modified forms which my improved gun may assume, the recoil-collar being pinned to the receiver instead of being screwed thereupon.

60

Fig. 14, a view in vertical transverse section showing the modified recoil-collar in front elevation.

Fig. 15, a broken view in side elevation of the forward end of the modified receiver.

65

Fig. 16, a broken plan view of another modified form of my invention.

My invention relates to an improved one-piece stock take-down firearm, the object being to provide a simple and convenient 70 arm constructed with particular reference to provision for throwing the recoil and the counter-recoil upon the stock and so protecting the take-down screw from strain.

With these ends in view my invention 75 consists in a one-piece stock take-down fire-arm characterized by having a recoil-collar mounted upon the receiver and isolated from the barrel, and by certain details of construction and combinations of parts as 80 will be hereinafter described and pointed out in the claims.

In carrying out my invention as herein shown, I employ a recoil-collar 17 having a depending recoil-taking lug 18, an upwardly-projecting sight-projection 19 and internal threads 20, which latter receive the responding external threads 21 of a stem 22 located at the forward end of the receiver 23 and separated therefrom by a 85 stop-shoulder 24, whereby the said collar is mounted upon the forward end of the receiver rather than upon the barrel 25 of the arm as has heretofore been proposed. The rear or recoil face 26 of the lug 18 90 of the collar is located in the plane of the rear face thereof, while the forward face of the lug is beveled as at 27 to facilitate the assembling of the arm.

For the reception of the recoil-collar 17 100 which in the preferred form, is larger in diameter than the body of the receiver, the one-piece stock 28 is formed with a transverse groove 29 corresponding in width to the width of the said collar. The rear 105 shoulder 30 of this groove coacts with the rear face of the collar in taking up the recoil, while the forward shoulder 31 of the groove coacts with the forward face of the collar in taking up the counter recoil.

110

For the reception of the recoil-taking lug 18 of the collar, the stock is formed with a recess 32 leading out of the bottom of the groove 29. The rear wall of the said recess 5 coacts with the recoil face 26 of the lug in taking the recoil.

The stem 22 of the receiver is formed with internal threads 33 which receive responding threads 34 formed upon the stem 35 of the barrel 25, which is separated from the said stem 35 by a shoulder 36. In this connection it is to be particularly noted that the external diameter of the shoulder 36 of the barrel is smaller than the internal 15 diameter of the recoil-collar 17, as clearly shown in Fig. 12, so that under no circumstances can the shoulder 36 of the barrel come in contact with the forward face of the collar, whereby the barrel is guarded 20 against being deformed by any tilting tendency of the collar at the time of recoil.

For fastening the receiver 23, the collar 17 and the barrel 25 to the one-piece stock 28, I employ a take-down screw 37 having a slotted and knurled head 38, a threaded end 39, and a circumferential groove 40, which latter receives a retaining-ring 41. For the reception of the screw 37, I employ a take-down bushing 42 having a 30 flanged head 43 and retaining-threads 44, this screw being forced or screwed into a hole 45 entering the lower face of the stock and centrally intersecting the recess 32 formed therein for the reception of the recoil-taking lug 18 as described. The stock is also formed with a recess 46 concentric with the hole 45 for the reception of the flanged head 43 of the bushing and the knurled portion of the head 38 of the screw 40. The bushing is provided at its outer 40 end with threads 47 responding to the threads of the threaded end of the screw 37 and permitting the take-down screw to be passed through the bushing 42, after 45 which the retaining-ring 41 is fitted into the circumferential groove 40 of the screw. The ring then coacts with the threads 44 to prevent the screw from dropping out of the bushing which is also provided with a counter-sink 48 and a slot or kerf 49.

The recoil-taking lug 18 is formed with a threaded screw-hole 50, the threads of which respond to the threads of the threaded end 39 of the take-down screw 37. As 55 the screw 37 is turned home into the lug 18, the lower faces of the receiver 23 and barrel 25 are firmly seated upon the bottom of the semicircular groove 51 formed in the stock 28.

Under the construction described, the recoil of the arm falls entirely upon the recoil-face 26 of the lug 18 and the rear face of the collar, the former bearing against the rear face of the recess 32 in the stock and 65 the latter bearing against the rear shoulder

30 of the groove 29 in the stock. The tendency of the collar 17 to tilt under the shock of the recoil, is reduced to the minimum by the engagement of the rear face of the recoil-collar with the shoulder 30 of the 70 groove 29, whereby the recoil-taking surfaces are carried upward toward the axis of the barrel in which the recoil is generated. Moreover, by mounting the recoil-collar directly upon the receiver instead of 75 upon the barrel as has been done before, the tendency of the collar to tilt is resisted by the relatively heavy receiver rather than by the relatively light barrel, which is thus protected against deformation. On the other 80 hand, the counter-recoil is entirely taken up by the impingement of the forward face of the collar upon the forward shoulder 31 of the groove 29 in the stock. Therefore, the entire shock of recoil and the entire 85 counter-recoil is removed from the take-down screw 37, upon which no transverse strain is thrown. Incidentally, the collar is concealed within the stock except as to its upper portion, whereas in the guns of 90 the prior art, the lug has been made of the same diameter as the stock, thus necessitating the use of a two-piece stock in which no provision can be made for taking the counter recoil by the stock itself.

The sight-projection 19 of the collar 17 lifts the line of sight above the heated barrel and virtually takes the place of a ventilated sight-rib which is both expensive and cumbersome. However this sight-projection will only be used when my invention is embodied in shot-guns as herein shown, my invention being equally applicable to rifles as I would have it clearly understood.

In Figs. 13 to 15 inclusive I have shown a modified construction in which the recoil-collar 52 corresponds to the collar 17 except in so far as it is secured to the receiver by means of a locking-pin 53 passing through a transverse groove 54 in the stem 55 of the receiver 56. In this case, the stem 55 is not provided with external threads nor is the collar provided with internal threads.

In Fig. 16 another modification is shown, in which the collar 57 and the receiver 58 are of the same external diameter, there being no groove in the stock to receive the collar 57; the recoil will be taken entirely by the lug (not shown) of the collar.

My improved gun, broadly viewed, comprises a one-piece stock-unit, and a rigid receiver-and-barrel unit, the latter being separable as one piece from the said stock-unit and provided with a recoil-taking collar the faces of which coact directly with the faces of the stock so as to take the shocks of the recoil and the counter-recoil, whereby the take-down screw (or other fastening means) employed to secure the receiver-and-barrel

unit and the stock-unit together is prevented from being hammered and deformed by the shocks of recoil and counter-recoil.

I claim:

5 1. In a one-piece stock take-down firearm, the combination with a one-piece stock, of a receiver, a recoil-collar mounted thereupon and transmitting the shocks of recoil directly to the said stock, and a barrel rigidly 10 mounted in the receiver without contact with the said collar, whereby the barrel is protected against injury.

15 2. In a one-piece stock take-down firearm, the combination with a one-piece stock having a transverse groove, of a receiver, a recoil-collar mounted thereupon and entering the said groove and coacting directly with the walls thereof to take the shocks of recoil and the counter-recoil, and a barrel rigidly 20 mounted in the receiver without contact with the said collar, whereby the barrel is protected against injury.

25 3. In a one-piece stock take-down firearm, the combination with a one-piece stock having a recess leading out of the bottom thereof, of a receiver, a recoil-collar mounted thereupon and formed with a depending recoil-taking lug the rear face of which engages with the rear wall of the said recess;

and a barrel rigidly mounted in the receiver 30 without contact with the said collar, whereby the shocks of recoil and the counter-recoil are transmitted by the said collar directly to the one-piece stock and whereby the barrel is protected from injury.

35 4. In a one-piece stock take-down firearm, the combination with a one-piece stock, of a receiver, a barrel rigidly mounted therein, a recoil-collar mounted upon the receiver, coacting directly with the one-piece stock to 40 take the shocks of recoil and the counter-recoil and making no contact with the said barrel; and fastening means mounted in the stock and engaging with the said collar for securing the receiver to the stock, whereby 45 by the shocks of recoil and the counter-recoil are transmitted by the collar directly to the one-piece stock and whereby the said barrel and fastening means are protected from injury.

50 In testimony whereof, I have signed this specification in the presence of two subscribing witnesses.

THOMAS C. JOHNSON.
